(57) **CLAIM**

The ornamental design for a display screen with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first image in a sequence for a display screen with graphical user interface showing our new design;

FIG. 2 is a partial enlarged view of the first image thereof; FIG. 3 is a partial enlarged view of a second image thereof; FIG. 4 is a partial enlarged view of a third image thereof; and,

FIG. 5 is a partial enlarged view of a fourth image thereof. The appearance of the image transitions between the images shown in FIGS. 2-5.

The process or period in which one image transitions to another forms no part of the claimed design.

The broken lines showing of the display screen and portions of the user interface form no part of the claimed design.
